UNITED STATES PATENT OFFICE.

JOSEPH S. H. LOVETT, OF TRENTON, NEW JERSEY, ASSIGNOR OF ONE-THIRD TO THEODORE PESSINGER PAYNE, OF NEWARK, NEW JERSEY, AND ONE-THIRD TO WILLIAM WALLACE NEAR, OF TORONTO, CANADA.

FEEDING MECHANISM FOR HOSE-MAKING MACHINES.

No. 889,940.

Specification of Letters Patent.

Patented June 9, 1908.

Application filed November 20, 1907. Serial No. 403,105.

To all whom it may concern:

Be it known that I, JOSEPH SCHENCK HOOKER LOVETT, of the city of Trenton, in the county of Mercer, in the State of New Jersey, one of the United States of America, have invented certain new and useful Improvements in Feeding Mechanism for Hose-Making Machines, of which the following is the specification.

10 My invention relates to improvements in feeding mechanism for hose making machines, and the object of the invention is to devise a machine which will quickly and automatically deliver the canvas, cut and prepared by the cutting machine, directly to the hose making machine and also attach the rubber strip forming the outside jacket of the hose to the canvas body preparatory to its being wound by the completing machine 15 and it consists essentially of a rectangular frame, T-shaped standards secured in bearings to each end of the frame and capable of vertical movement therein, mechanism actuated from the driving shaft of the cutting 20 machine for imparting such vertical movement to the T-shaped standards, rollers journaled at their end in the standard, supplementary bearing standards located at each end of the aforesaid frame, cross shafts journaled in the supplementary standards, pulleys mounted on the cross shafts intermediately of the rollers, belts extending between the pulleys at each end of the frame and located between the rollers journaled in 25 the main frame, mechanism for driving the belts from the main drive of the cutting machine, grooved wheels secured on pivoted arms in proximity to each end of the machine and means for adjusting the height of 30 such wheels as hereinafter more particularly described by the following specification.

Figure 1 is a general perspective view of my machine attached to the driving mechanism of a cutting machine. Fig. 2 is a plan view of my machine. Fig. 3 is an enlarged cross section of my machine.

In the drawings like letters of reference indicate corresponding parts in each figure.

50 A is the main frame, rectangular in form. A' are vertical bearings located to the inside of the end bars of the frame A.

B are T-shaped standards the stem B' of which are held in the bearings A' and the

cross heads B² of which are provided with bearing notches B³.

55

B⁴ are a series of rollers extending longitudinally of the frame and having pintles extending from the end thereof which rest in the bearing notches B³.

C is a driving shaft, driven from a suitable 60 source of power and journaled in bearing bracket C' in the base of the frame A.

C² is a pulley thereon and C³ is an endless cord or belt extending around the pulley C² and around the grooved portions B⁵ of the 65 rollers B⁴.

B⁶ is a rock shaft journaled in the brackets in the main frame A.

B⁷ is an arm secured to the rock shaft B⁶.

B⁸ are cams secured to the main driving 70 shaft D of the cutting machine D'.

B⁹ is a link pivotally connected at one end to the arm B⁷. The other end of the link B⁹ is provided with rollers B¹⁰ engaging with cam grooves formed in the inner faces of the 75 cams B⁸. These grooves are of any shape suitable for imparting a rocking movement to the arm B⁷ through the link B⁹.

B¹¹ are cam arms secured to the shaft B⁶ and engaging the lower end of the stems B.

80 E, E' are supplemental bearing standards.

E², E³ are cross shafts journaled in suitable bearings.

E⁴, E⁵ are series of pulleys located opposite the space between each pair of rollers B⁴ 85 at each end of the machine respectively.

E⁶ are endless belts extending around each pair of pulleys, E⁴ and E⁵, located between each pair of rollers B⁴.

The shaft E² extends beyond its bearing 90 standards towards the cutting machine D' and is provided with a bevel pinion E⁷.

E⁸ is a supplementary shaft journaled in bearing in the main frame of the cutting machine.

95

E⁹ is a bevel gear secured to the end of the shaft E⁸ and meshing with the pinion E⁷ in the shaft E².

E¹⁰ is a ratchet wheel secured to the shaft 100 E⁸.

E¹¹ is a rock arm swung on the shaft E⁸ and E¹² is a pawl engaging with the ratchet E¹⁰.

E¹³ is a link pivoted to the rock arm E¹¹ and provided with rollers E¹⁴ at its opposite end.

105

E¹⁵ is a cam secured to the main driving

shaft D provided with a cam groove E¹⁶ with which the rollers E¹³ engage so as to impart a rocking movement to the arm E¹¹.

5 F are arms swung on each end of the shafts E² and E³.

F' is a cross shaft journaled in the upper ends of the arms F.

10 F² are grooved wheels secured to the inner ends of the shafts. The arms F are held in an inclined position by the counterweights F³.

15 F⁴ are trains of gear connecting the shafts E² and F' and the shaft E³ with its corresponding shaft F'. The gears are proportioned so as to drive the wheels F² in unison with the belts E⁶.

The arms F are provided with extensions F⁵ extending at right angles to, and opposite to the pivot points of the arms.

20 F⁶ is a lever and quadrant which are connected by links F⁷ to the extensions F⁵. By this arrangement the height of the wheels may be adjusted to suit various thicknesses of material.

25 Having described the principal parts involved in my invention, I shall briefly describe the operation of the same. The steel pole 2 on which is held the rubber tube 3 forming the base of the hose is placed in position in the grooves of the wheels F². The 30 canvas as it passes from the cutting machine, is drawn by the revolving rollers B⁴ into the table A. The required width of material 4, (see Fig. 3) is fed into the table and severed from the main body and the cam B⁸ operates.

35 It will be noticed in referring to Fig. 3 of the drawing that the inner edge of the canvas falls when cut from the main body onto rubber covered pole to which it is suitably cemented. By the operation of the cam B⁸, 40 the cam arms B¹¹ are rocked from beneath the stems B' of the T-standards B. The standards B and the rollers mounted thereon are depressed thereby lowering the portion of canvas or other material supported thereby onto the belts E⁶.

45 The belts are then revolved by means of the cams E¹³ which rotate the shaft E⁸ through the ratchet and pawl E⁹, the shaft E⁸ being connected by the bevel gears E⁷ and E⁹, to the shaft E². The 50 belts E⁶ are revolved sufficiently by one movement of the ratchet and pawl E⁹ to convey the canvas almost past the front of the cutting machine.

55 The rear end of the canvas strip is thereby left in front of the cutting machine so that the next piece of canvas as it is fed from the machine overlaps the one previously fed enabling the strips to be cemented together end to end. The rollers H press these end portions together as 60 the canvas is conveyed forwardly.

E are pulleys placed intermediately of the pulleys E⁵ and support the belts E¹⁵ which serve to carry the canvas on to the hose making machine.

65 5 is the rubber jacket or outer cover of the

hose which is cemented onto the outer edge of the canvas previously to its being fed forward by the conveyer belts. The outer roller H forces the cemented portions of the jacket and canvas together.

70 From this description it will be seen that I have devised a simple form of conveyer which will quickly and automatically feed the canvas from the cutting machine to the hose making machine.

75 What I claim as my invention is:

1. A feeding mechanism for hose making machines comprising a series of revoluble rollers suitably supported and journaled, and intermediate belt conveyers suitably supported and driven, and means for transferring the canvas from the rollers to the belts, as and for the purpose specified. 80

2. A feeding mechanism for hose making machines comprising a series of revoluble belts, a series of revoluble rollers arranged longitudinally between, and alternately with the belts and means for transferring the canvas from the rollers to the belts as and for the purpose specified. 85

90 3. A feeding mechanism for hose making machines, comprising a main frame, end standards capable of vertical movement in the frame, rollers journaled in the standards, means for imparting vertical movement to the standards, and revoluble belts arranged between each pair of rollers, as and for the purpose specified. 95

4. A feeding mechanism for hose making machines comprising a main frame, end standards capable of vertical movement in the frame, rollers journaled in the standards, cams supporting such standards and designed to lower the same, belts located between the rollers and means for revolving the belts 100 upon the lowering of the standards as and for the purpose specified. 105

5. In a feeding mechanism for hose making machines, the combination with the main frame having vertical end bearings and the standards provided with depending stems, held in the vertical bearings in the frame, rollers journaled in the standards, means for revolving the rollers as the canvas is fed thereon, means for depressing the standards upon the completion of the lateral feed of the canvas and means for conveying the canvas longitudinally upon the depression of the rollers as and for the purpose specified. 110 115

6. In a feeding mechanism for hose making machines, the combination with the main frame, of depressible rollers journaled therein, means for revolving the rollers as the canvas is fed thereon, means for depressing the rollers upon the completion of the lateral feed of the canvas and means for conveying the canvas longitudinally upon the depression of the rollers, as and for the purpose specified. 125 130

7. In a feeding mechanism for hose making machines, the combination with the main frame, of depressible rollers journaled therein, means for revolving the rollers as the canvas is fed thereon, means for depressing the rollers upon the completion of the lateral feed of the canvas, conveyer belts located between each pair of rollers and means for revolving the belts upon the depression of the rollers as and for the purpose specified. 50
8. In a feeding mechanism for hose making machines, the combination with the main frame provided with vertical end bearings T-shaped standards, having depending stems held in the bearings in the frame; rollers journaled in the heads of the standards, a rock shaft journaled in the frame, cam arms thereon on which the stems of the standards rest, and a cam on the drive shaft, an arm in the rock shaft, a link pivotally connected to the arm and provided with rollers engaging with cam on the main drive shaft and means for conveying the canvas longitudinally upon the depression of the rollers, as and for the purpose specified. 60
9. In a feeding mechanism for hose making machines, the combination with the main frame provided with vertical end bearings, T-shaped standards having depending stems held in the bearings in the frame, rollers journaled in the heads of the standards, a rock shaft journaled in the frame, cam arms thereon on which the stems of the standards rest, and a cam on the drive shaft, an arm in the rock shaft, a link pivotally connected to the arm and provided with rollers engaging with cam on the main drive shaft, supplemental standards located at each end of the main frame, cross shafts journaled thereon, 75 pulleys mounted thereon, belts extending between the pulleys and located between each pair of rollers and means for revolving the same upon the depression of the rollers as and for the purpose specified. 80
10. In a feeding mechanism for hose making machines, the combination with the main frame, the depressible rollers, and the main driving shaft, of supplemental bearings 85
- located to each end of the main frame, cross shafts journaled thereon, pulleys mounted thereon, endless belts extending between the pulleys and located between the rollers, a cam on the main shaft, a supplemental shaft, a ratchet thereon, a rock arm and pawl swung on the supplemental shaft and bevel gears connecting the supplemental shaft with one of the cross shafts of the belt conveyer as and for the purpose specified. 90
11. In a feeding mechanism for hose making machines, the combination with the depressible rollers and the intermediate belt conveyers of a series of spring held compressor rollers designed to extend crosswise of the conveyer at the delivery end thereof as and for the purpose specified. 65
12. In a feeding mechanism for hose making machines, the combination with depressible rollers and intermediate belt conveyers, of grooved wheels journaled at each end and at the side of the conveyers as and for the purpose specified. 70
13. In a feeding mechanism for hose making machines, the combination with the depressible rollers and intermediate belt conveyers, of grooved wheels journaled at each end and at the side of the conveyers and driving means for rotating the wheels in unison with the belts, as and for the purpose specified. 75
14. In a feeding mechanism for hose making machines, the combination with the depressible rollers and intermediate belt conveyers, of arms pivotally swung intermediate of their length, grooved wheels located at one end of the arms and counterweights at the other end of the arms, right angular extensions extending from the pivot points of the arms, an adjusting lever and quadrant and links connecting the levers with such right angular extensions as and for the purpose specified. 85
